METHOD OF AND APPARATUS FOR MOISTENING YARNS.

1,090,971.

Specification of Letters Patent.

Patented Mar. 24, 1914.

Application filed July 2, 1912. Serial No. 707,170.

To all whom it may concern:

Be it known that I, OSBORN H. CILLEY, a citizen of the United States, residing at Westford, in the county of Middlesex and State of Massachusetts, have invented a new and useful Method of and Apparatus for Moistening Yarns, of which the following is a specification.

This invention has for its principal object the efficient, quick, and uniform moistening of yarn wound either on cones, tubes, or bobbins so that the yarn may be used in subsequent processes with a high degree of efficiency.

Another object of the invention is to provide for the conditioning or moistening of worsted top and goods of similar character.

Reference is to be had to the accompanying drawing, in which the figure is a side elevation, with parts broken away to show interior construction, of a preferred embodiment of the invention.

It is well known that after being spun, yarn retains its tendency to kink, due to its twist, and if the filling is not aged sufficiently and the twist thus set, as it is unwound from the bobbins, tubes, or cops, it will cause serious imperfections in the finished goods and interfere with the efficient handling of the yarn during the operations which it passes through in the mill. On this account moisture is generally introduced into yarn, and it is also brought to a fixed standard, but it has been found rather difficult to accomplish this readily and to make the moisture content of the yarn uniform, particularly where it is wound on cones or cross-wound to a comparatively great depth. Under ordinary circumstances the yarn standing for a number of hours in a room with the humidity near the dew point will take up the proper percentage of moisture only on the outside layers, particularly if it is cross-wound. It has been found also that if the yarn is used in rooms which are not themselves kept moist, the moisture will leave the yarn and this lessens the strength of the yarn, it being well understood that when the yarn contains the proper amount of moisture it is stronger than otherwise.

Referring to the drawings and in detail, they show a main cylinder or chamber 10 provided with a door 11 at one end which is

adapted to be removed when the chamber is to be charged or emptied. Extending upwardly from the bottom of this chamber is a pipe 12 having a valve and connected at its upper end with a water charging receptacle 13 having a water glass 14 connected with it at the top and bottom. This water glass of course is graduated so that the amount of water in the receptacle at all times can be ascertained. At the bottom of the chamber 10 is a surface evaporator 15 adapted to be filled by water from the pipe 12. It is provided with a double bottom and has a steam coil therein provided with an inlet 16 and an outlet 17 for the steam. The chamber is connected at any convenient point by means of a pipe 20 with an air pump 21 operated in any desired way.

The apparatus is used and the method is carried out in the following manner. The yarn is first weighed and the operator decides how much moisture is to be introduced into the yarn. Then he opens the valve 12 allowing the amount of water which he wishes to introduce into the yarn to run into the evaporator and then shuts off the flow. The air is then exhausted from the cylinder or chamber 10 by means of the air pump and steam is allowed to pass into the coil in the evaporator. Under ordinary conditions a 28-inch vacuum is provided with the barometer at 30-inches. The water which has been drawn into the evaporator will pass into vapor at 101°, and consequently the yarn does not have to be heated up materially above the temperature of the rooms in which it is to be used, and it cannot be injured by the heat employed. Nor is the water lost from the yarn so readily as it would be if introduced at a higher temperature. The heat is kept on until the water in the evaporator has been entirely evaporated, and as it is in the form of vapor it passes directly into the yarn and replaces the air which has been exhausted previously. Those yarn layers which are nearest the center of the tube, bobbin or cop receive as much moisture as those on the outside, because the air has been exhausted from them and the moisture is the only thing that can take its place. When all of the water in the evaporator has been vaporized the steam, of course, is shut off and the temperature in

cop. Although I have illustrated and described a preferred embodiment of the invention, and a simple method of carrying out the invention, I am aware that modifications can be made therein by any person skilled in the art without departing from the scope of the invention as expressed in the claims. Therefore, I do not wish to be limited to all the details herein shown and described, but

What I do claim is:—

the detail. What I do claim is:—

1. A method of moistening yarn which
25 consists in placing the yarn in a receptacle
having a surface evaporator entirely in-
closed therein, placing a predetermined
quantity of water on said evaporator within
said receptacle, reducing the air pressure in
30 said receptacle and evaporating the water
by heating said evaporator by steam circu-
lating within the evaporator but out of con-
tact with the water thereon.

2. A method of moistening yarn, which
35 consists in inclosing the yarn in an air-tight
receptacle, supplying a predetermined quan-
tity of water to said receptacle, exhausting

the air from the receptacle, and completely evaporating said water in said receptacle.

3. An apparatus for moistening yarn having in combination an air tight chamber for the yarn, means for exhausting the air therefrom, a surface evaporator therein, means for introducing a measured quantity of water into the evaporator, and means for heating the evaporator and completely evaporating the water therein thereby causing a predetermined quantity of moisture to be added to the yarn. 40 45 50

4. An apparatus for moistening yarn having in combination an air tight chamber for the yarn, a surface evaporator therein, a receptacle for water outside the chamber having a gage for showing the amount of water in said receptacle, and a pipe with a valve therein connecting said receptacle to said evaporator whereby a predetermined quantity of water as shown by the gage may be introduced through the pipe and valve into said evaporator within said chamber. 60

5. In an apparatus for moistening yarn, the combination of a closed chamber for the yarn, a surface evaporator inclosed therein, means for introducing a measured quantity of water into said evaporator and means for entirely evaporating said water. 35
whereof I have hereunto set

In testimony whereof I have hereunto set my hand, in the presence of two subscribing witnesses.

OSBORN H. CILLEY.
